UNITED STATES PATENT OFFICE

CLYDE B. ROBINETTE, OF CLEVELAND, OHIO

DESIGN FOR A TABLE COVER

Application filed October 23, 1930. Serial No. 37,354. Term of patent 7 years.

To all whom it may concern:

Be it known that I, CLYDE B. ROBINETTE, a citizen of the United States, residing at Cleveland, in the county of Cuyahoga and State of Ohio, have invented a new, original, and ornamental Design for Table Covers, of which the following is a specification, reference being had to the accompanying drawing, forming part thereof.

The figure is a plan view of a table cover, showing my new design.

Having thus disclosed my invention, I claim:

The ornamental design for a table cover, as shown.

CLYDE B. ROBINETTE.
